UTENSIL INCORPORATING A WRITING IMPLEMENT AND CIGARETTE HOLDER

Heinz Gossler, Heidelberg, Germany

Application October 26, 1956, Serial No. 618,528

Claims priority, application Germany October 27, 1955

4 Claims. (Cl. 131—178)

This invention relates to a combination writing implement and smoker's holder for cigarettes and like articles.

It has already been proposed to combine a writing implement with a holder for smoker's articles wherein the mouthpiece of the cigarette holder contains in its hollow bore a writing implement in the form of a ballpoint pen, fountain pen or the like, said mouthpiece also forming a closure cap over the writing implement when the latter is not in use and becoming a part of the cigarette holder having a sleeve-shaped end for the insertion of the cigarette. If the writing implement is to be used, then the mouthpiece is connected with its end over the sleeve-shaped end of the writing implement and forms a prolongation of the writing implement.

The body or barrel containing the writing implement proper is equipped with guide channels serving for the passage of smoke, whereby in the front end near the tip of the writing implement small holes are provided which permit the flow of cigarette smoke therethrough.

The present invention distinguishes from the known combination writing implement and smoker's holder for cigarettes in that it proposes the employment of filter means for the cigarette smoke as well as ejector means for the cigarette butt.

It is, therefore, an object of the present invention to provide means facilitating the rapid conversion of a cigarette holder to a writing implement and conversely a speedy change of the writing implement to a cigarette holder.

It is a further object of the present invention to provide means facilitating the accommodation of useful articles, such as a ballpoint pen, in the bore of a hollow member, such as a barrel, which forms simultaneously a receptacle for a filter without interfering with the efficiency of a cigarette holder.

It is still another object of the present invention to provide means affording the combination with the barrel of the ballpoint pen and a protection for the filter housed therein and simultaneously facilitating the ejection of the cigarette butt when used as a cigarette holder.

It is further an object of the present invention to provide means envisaging the employment of a writing implement which is provided with grooves which, in turn, when the writing implement is in assembled condition with said barrel, establish with the inner wall thereof passageways for the smoke to travel therethrough when the writing implement is converted into a cigarette holder.

These and other objects of the invention will become further apparent from the following detailed description, reference being made to the accompanying drawing showing preferred embodiments of the invention.

In the drawing:

Fig. 1 is a utensil embodying the invention and showing in section a writing implement with filter and ejector together with a mouthpiece for a cigarette holder.

Fig. 2 illustrates a utensil in somewhat modified form,

2

shown in section, with filter, ejector and mouthpiece in different position.

Fig. 3 is a section of a utensil in further modified form.

Fig. 4 is a side view of the writing implement showing a groove in a side thereof.

The combination smoking and writing implement hereinafter explained in greater detail may be manufactured from various materials, such as wood, resinous material, ivory, meerschaum, metal and the like, and these various materials can also be combined with each other to make up the aforesaid combination implement.

Referring now more particularly to the drawing, there is shown in Fig. 1 a combination writing implement and

holder for smoker's articles made in accordance with the present invention. Such utensil 20 consists principally of a barrel 1 having internal threads at 4 and 4a. These threads may be used for the connection with a writing implement, such as a ballpoint pen 2, the forward end 2a of which has external screw threads to engage the screw threads 4 or 4a as desired.

According to Fig. 1, the writing implement 2, 2a is engaged with the threads 4a of the barrel 1 and this writing implement has adjacent its conical part at the forward end grooves 3, which, when the forward end 2a is threadedly engaged with the barrel 1, provide channels or passage means, which permit air or smoke to pass therethrough into the interior of the barrel 1. The writing implement 2 has a cartridge 2b which is smaller than the inner diameter of the barrel 1, so that a ring-shaped space 1a is created within the barrel when the writing implement 2 is fixed therein.

Rearwardly of writing implement 2 and within barrel 1 there is positioned a filter cartridge 6 which may be held in position in any appropriate manner.

The outer end portion 1b of barrel 1 is somewhat reduced in diameter and shaped to frictionally receive thereon part 5 of an ejector device 21. This ejector device consists of the upper part 5 from which extends a tube 7 communicating with the hollow upper part 5. Tube 7 is surrounded by a coil spring 8, which is seated at one end on a shoulder 5a of part 5 and is seated at its other end against a partition 10 provided within ejector sleeve 9. Tube 7 is slidable through an opening in partition 10 and carries a disk 11 which is either threaded on or in any way connected with the outermost end of tube 7. It thus becomes apparent that upon sliding movement of ejector sleeve 9 in the direction of arrow A a cigarette butt seated within holder 9a will be readily pushed outwardly by means of disk member 11 whereby partition 10 compresses coil spring 8 during such movement.

Over the forward part 2a of the writing implement 2, there is seated a mouthpiece 12 which frictionally engages the outer surface of barrel 1. The mouthpiece 12 has the channels 12a and 12b, the latter being sufficiently wide to receive the forward end 2a of the implement and to establish communication through the passageways 3.

Referring now more particularly to Fig. 2, there is shown in longitudinal section the ejector device 21 hereinafter described in greater detail, which in this particular instance is frictionally engaged with the outer surface of barrel 13 at one end of the latter. Into this one end of barrel 13 there is inserted and affixed thereto (by means of threads or like connecting means) a writing implement 2 having the forward or conical part 2c and the reservoir 2d terminating in an end 2e. In the forward end 2c there are provided holes or openings 14 communicating with the ring-shaped space 13a in barrel 13 and further with the interior of stationary tubular member 5 of the ejector device 21.

Barrel 13 is provided with another end 13b which is threaded at 16 to threadedly fasten thereto a mouthpiece 15 having channels 15a and 15b. Rearwardly of the reservoir of the writing implement 2 adjacent 2e is inserted a filter cartridge 6 of known construction.

While according to Fig. 1 the mouthpiece may be readily removed from the forward end 2a of the ballpoint pen and then placed in engagement with sleeve 9 and over holder 9a, in the embodiment shown in Fig. 2, the stationary member 5, when the utensil 30 is not to be used as a cigarette holder as shown, may be readily withdrawn from the forward end of the writing implement 2 and may then be capped over the mouthpiece 15 so as to provide a prolongation of barrel 13.

Thus the utensil may be used either in the position of writing or in the position of working as a cigarette holder containing a filter cartridge as well as a ballpoint pen reservoir and an ejector device for the cigarette butt.

According to Fig. 3, the mouthpiece 15c is screwed at 16 internally to one end of barrel 13 and contains filter cartridge 6 which extends from the mouthpiece 15c into the barrel 13c. Within barrel 13c there is arranged a writing implement 2f having the reservoir 2g and the forward end 2h provided with openings 14. In this particular embodiment only the stationary hollow member 17 is placed over the forward end 2h for frictional engagement with the outer surface of the barrel 13c. This instrument may be readily used as a cigarette holder whereby the cigarette is placed with one of its ends in holder sleeve 9b. The stationary hollow member 17 is further provided with a partition 17a for the connection with a known ejector device (not shown).

It will be readily seen from the foregoing disclosure that the new combination writing implement and cigarette holder may receive a filter cartridge which is readily exchangeable or replaceable, as it is only necessary to unscrew the mouthpiece or the ejector device at 16 or 1b to remove the used cartridge.

Likewise the refill or reservoir 2b, 2d or 2f may be readily replaced by unscrewing the forward part of the ballpoint pen from the respective barrel. This forward end as pointed out hereinabove possesses one or more longitudinal grooves which, when the ballpoint pen with reservoir is connected with the respective barrel end, provide passageways from the front end of the barrel into the interior thereof. The mouthpiece as aforesaid may be either screwed to the other end of the barrel or placed in frictional engagement with the barrel and over the forward end of the writing implement or may be frictionally connected with the ejector device as hereinabove explained. The ejector device may also be placed either over the forward end of the ballpoint pen or over the mouthpiece of the cigarette holder to thereby convert the instrument either into a writing implement with prolonged barrel portion or to a cigarette holder with ejector and filtering means seated in said barrel.

It can thus be seen that there has been provided according to the invention a utensil which is characterized by a hollow member forming a barrel with two ends, at least one of said ends of said barrel being provided with inner threads, a writing implement including a forward part and a reservoir with a rearward end, said forward part being provided with threads for engagement with the threads of said one end of said barrel, a mouthpiece having an opening for frictionally engaging said barrel over said forward part of said implement in one position of said mouthpiece, filtering means within said barrel between the other end thereof and the rearward end of said reservoir, ejector means provided with a stationary, hollow member adapted to be capped over the other end of said barrel.

The stationary member has a tubular extension and an ejector sleeve slidable relative to said stationary member, said ejector sleeve being supported by a coil spring surrounding a tubular extension and seated with one end on

said stationary member, and a partition in said ejector sleeve against which the other end of said coil spring abuts. The opening of said mouthpiece is dimensioned to be engaged with and placed over said ejector sleeve for frictional engagement therewith in another position; said forward part of said writing implement is provided with longitudinal grooves extending substantially parallel to the axis of said reservoir. The reservoir is reduced in diameter relative to the hollow barrel to permit passage of smoke from said ejector device through said filtering means and said barrel past said writing implement in said one position of said mouthpiece.

Various changes and modifications may be made without departing from the spirit and scope of the present invention and it is intended that such obvious changes and modifications be embraced by the annexed claims.

Having thus described the invention, what is claimed as new and desired to be secured by Letters Patent is:

1. A utensil of the character described comprising a hollow member forming a barrel with two ends, both said ends being provided with inner threads, a writing implement having a rearward part and a forward part, said forward part being provided with threads for engagement with the threads of one of the ends of said barrel, a mouthpiece provided with threads for engagement with the threads of the other end of said barrel, filtering means within said barrel between said other end thereof and the rearward end of said writing implement, ejector means provided with a stationary, hollow member having a tubular extension, an ejector sleeve slidable relative to said stationary member, said ejector sleeve being supported by a coil spring surrounding said tubular extension and seated with one end on said stationary member, and a partition in said ejector sleeve against which the other end of said coil spring abuts, said stationary member being adapted to be placed over said forward part of said writing implement for frictional engagement with said one end of said barrel in one position and over said mouthpiece for frictional engagement with the other end of said barrel in another position, said forward part of said writing implement being provided with longitudinal peripheral grooves, which when said forward part is threadedly engaged with said one end of said barrel form passageways with the latter for guiding smoke passing from a cigarette placed in said ejector means through said filtering means, past rearward part of said writing implement into said mouthpiece.

2. A utensil of the character described comprising a hollow member forming a barrel with two ends, at least one of said ends of said barrel being provided with inner threads, a writing implement including a forward part and a reservoir with a rearward end, said forward part being provided with threads for engagement with the threads of said one end of said barrel, a mouthpiece having an opening for frictionally engaging said barrel over said forward part of said implement in one position of said mouthpiece, filtering means within said barrel between the other end thereof and the rearward end of said reservoir, ejector means provided with a stationary, hollow member adapted to be capped over the other end of said barrel, said stationary member having a tubular extension, an ejector sleeve slidable relative to said stationary member, said ejector sleeve being supported by a coil spring surrounding said tubular extension and seated with one end on said stationary member, and a partition in said ejector sleeve against which the other end of said coil spring abuts, the opening of said mouthpiece being dimensioned to be engaged with and placed over said ejector sleeve for frictional engagement therewith in another position, said forward part of said writing implement being provided with longitudinal grooves extending substantially parallel to the axis of said reservoir, said reservoir being reduced in diameter relative to the hollow barrel to permit passage of smoke from said ejector device through

said filtering means and said barrel past said writing implement in said one position of said mouthpiece.

3. A utensil of the character described comprising a hollow barrel forming member terminating in two ends provided with threads, a writing implement with a forward part and with a reservoir terminating in a rearward end, said forward part being provided with threads for engagement with the threads of said one end of said barrel, a mouthpiece provided with a threaded end for engaging said other end of said barrel, filtering means within said barrel between the rearward end of said reservoir and said threaded end of said mouthpiece, ejector means provided with a stationary hollow member adapted to be capped over the one end of said barrel at said forward part of said implement, said stationary member having a tubular extension, an ejector sleeve slidable relative to said stationary member, said ejector sleeve being supported by a coil spring surrounding said tubular extension and seated with one end on said stationary member, a partition in said ejector sleeve against which the other end of said coil spring abuts, and means to retain said ejector sleeve on said stationary member, the opening of said ejector sleeve being dimensioned to be engaged with and placed over said mouthpiece for frictional engagement therewith, said forward part of said writing implement being provided with longitudinal grooves extending substantially parallel to the axis of said reservoir, said reservoir being reduced in diameter relative to the hollow barrel to permit passage of smoke from a cigarette when placed in said ejector device through said filtering means and said grooves to said mouthpiece.

4. A utensil of the character described comprising a hollow barrel forming member having a threaded end, a writing implement threadedly secured to said threaded end, said writing implement having a reservoir extending into said member and being spaced from the inner walls of the hollow member to form an annular space, a mouthpiece detachably engaged with said member, filtering means, at least a portion of said filtering means being disposed in said barrel, ejector means provided with a stationary tubular member, said tubular member being engaged with said barrel and having a tubular extension, an ejector sleeve slidable relative to said tubular member, said ejector sleeve being supported by a coil spring surrounding said tubular extension and seated with one end on said tubular member, a partition in said ejector sleeve against which the other end of said coil spring abuts, said writing implement having grooves therein communicating with said annular space to permit passage of smoke from a cigarette when placed in said ejector device through said filtering device to said mouthpiece.
